UNITED STATES PATENT OFFICE.

DEWITT T. SMITH, OF SCIO, OHIO.

INTERNAL-COMBUSTION ENGINE.

1,121,678.

Specification of Letters Patent. Patented Dec. 22, 1914.

Application filed August 26, 1912. Serial No. 717,102.

To all whom it may concern:

Be it known that I, DEWITT T. SMITH, a citizen of the United States, residing at Scio, in the county of Harrison, State of Ohio, have invented certain new and useful 5 Improvements in Internal-Combustion Engines; and I do hereby declare the following to be a full, clear, and exact description of the invention, such as will enable others skilled in the art to which it appertains to 10 make and use the same.

This invention relates to internal combustion engines and has for an object to provide an opposing cylinder one-cycle engine 15 having a novel mechanism for purging the cylinders of burnt gases and for feeding the fresh mixture to the cylinders immediately after the purging operation.

A further object of the invention is to provide a novel fuel reservoir from which a 20 predetermined quantity of gasoline is taken and forced under pressure into the cylinders at the ends of the working strokes of the piston.

With the above objects in view the invention consists of certain novel details of construction and combination of parts herein-after fully described and claimed, it being understood that various modifications may 30 be made in the minor details of construction within the scope of the appended claims.

In the accompanying drawings forming part of this specification:—Figure 1 is a 35 plan view of the engine. Fig. 2 is a side elevation of the engine. Fig. 3 is a reverse side elevation of the engine. Fig. 4 is a horizontal sectional view through the engine. Fig. 5 is an end elevation of the engine. Fig. 6 is a horizontal sectional view 40 through the engine cylinder showing the valves in position to hold the exhaust ports open during the scavenging operation. Fig. 7 is a horizontal sectional view through the engine cylinder showing the valves in position to close the exhaust ports during the intake of fuel. Fig. 8 is a vertical sectional view through the fuel reservoir.

Referring now to the drawings in which 50 like characters of reference designate similar parts, the engine is shown to comprise a bed frame 10 upon which is fixed opposing cylinders 11 and 12, there being a single piston 13 working in the cylinders and having 55 a transversely fixed shaft 14 which works terminally in aligned guide slots 15 formed in

the common base ends of the cylinders. The ends of the shaft 14 are connected to a crank shaft 16 through the instrumentality of connecting rods 17 which serve to rotate the 60 crank shaft during reciprocation of the piston.

Disposed in the walls of the cylinders are exhaust ports 18, both ports being disposed on the same sides of the cylinders. Air 65 ports 19 are disposed diametrically opposite and between the ports 18, these air ports being connected by a common branched pipe 20 to an air compressor. The air ports are exposed by the piston passing therebeyond 70 immediately after the exhaust ports are exposed by the piston, with the result that all burnt gas is immediately blown out by the purging air from the air pipes.

Disposed on the same sides of the cylinders as the air ports, and between the air ports, are fuel intake ports 21, these ports being connected by a common branched pipe 22 to the above mentioned air compressor which will be presently described. As the 80 piston passes beyond the air ports during the working stroke, the intake ports 21 will be exposed, and the fuel will be blown in through the branch pipe 22 and accumulate in the head of the cylinder ready to be compressed upon the compression stroke of the piston, both the exhaust and air ports being closed prior to opening of the intake ports by a mechanism which will now be described.

By referring to Fig. 6 it will be seen that arranged on opposite sides of the cylinders are slide valves 23 and 24 corresponding respectively to the exhaust and air ports, the slide valves having stems 25 and 26 95 which are provided with spaced lugs 27 and 28, corresponding lugs of both valves being engaged by the shaft 14 as the piston moves to one end of its stroke with a resultant shifting of the valve to open or closed position, both slide valves serving to expose the exhaust and air ports as the piston passes therebeyond during the working stroke, and serving to close the exhaust and air ports as the piston exposes the fuel intake ports 100 on its working stroke. By virtue of the lugs being spaced, the valves will be quiescent during the short interval required to permit of the shaft engaging with the idle set of lugs on the beginning of the compression stroke, so that the exhaust and air ports will be closed until the piston passes

therebeyond on the compression stroke, and thus leakage of the fresh fuel prevented.

An air compressor 29 is provided centrally with a diaphragm 30 in which is disposed a valve 31. The plunger 32 works in the compartment on one side of the diaphragm and is connected to the crank shaft by an eccentric rod 33. The diaphragm divides the air compressor into two compartments 34 and 35, and the air pipe 20 is connected to the compartment 35 in which the plunger works, the fuel pipe 22 being connected to the compartment 34, and further being connected to a gasoline or other fuel reservoir which will be presently described. The valve 31 is in the nature of a check valve which permits of air passing from the plunger chamber 35 into the chamber or compartment 34 but prevents retrograde movement of the air to the plunger chamber.

The air from the plunger chamber passes direct through the air pipe into the cylinders upon the air valves being exposed, but the air from the chamber 34 takes up the fuel before passage into the cylinders, and to attain this end I provide an upstanding dome-shaped air-tight reservoir 36 which is provided in one side at the bottom with an outlet opening 37, and is further provided with an integral cup-shaped chamber 38 through which the fuel pipe 22 passes, it being understood that the pipe is cut away within the chamber so that the chamber forms an enlarged continuation of the pipe. The chamber is provided with an inlet opening 39 which registers with the outlet opening 37 of the reservoir.

It will be noted that by reason of the peculiar construction of this reservoir the fuel will flow through the passage 37 into the chamber 38 until the weight of the column of liquid within the reservoir is balanced by the difference in air pressure without and within such reservoir. Under these conditions when the air is discharged from the chamber 34 the fuel in the chamber 38 will be blown through the pipe 22 while at the same time air is permitted to enter

through the opening 39 and bubble up 50 through the fluid in the reservoir so that when the blast of air from the chamber 34 ceases the chamber 38 is again filled.

In operation, an explosion occurs alternately at the outer limit of movement in 55 each direction of the piston, the fresh charge of fuel mixed with air from the air compressor being compressed in advance of the piston as it moves to the outer limit of its stroke and then being fired through the 60 instrumentality of spark plugs 40 carried in the cylinder heads.

What is claimed, is:—

1. The combination with an internal combustion engine of an air compressor, an air-tight fuel reservoir having a combined air inlet and fuel outlet opening in one side at the bottom, an air pipe connected to an air compressor and to the engine cylinder, and a fuel chamber carried by said fuel reservoir forming a continuation of said pipe and having an inlet opening in registration with the combined air and fuel outlet opening of said receptacle. 70

2. The combination with an internal combustion engine of an air compressor having an internal diaphragm dividing the compressor into two compartments, a check valve in said diaphragm, an air pipe leading from one of said compartments to said cylinder and adapted to purge the cylinder of burnt gases near the end of the exhaust stroke of the engine piston, an air pipe leading from the other of said compartments to said cylinder and adapted to be 80 exposed by said piston after the purging operation of the first named air pipe, and a fuel reservoir having an extension forming a continuation of the second named air pipe, said extension being adapted to be alternately filled from said reservoir and emptied by said second named air pipe. 90

In testimony whereof, I affix my signature, in presence of two witnesses.

DEWITT T. SMITH
